UNITED STATES PATENT OFFICE

158,643

COMBINED STAND AND PERFUME BOTTLE HOLDER

Frederick M. Breen, White Plains, N. Y., assignor to Coty, Inc., New York, N. Y., a corporation of Delaware

Application September 7, 1949, Serial No. 4,874

Term of patent 14 years

(Cl. D86—10)

To all whom it may concern:

Be it known that I, Frederick M. Breen, a citizen of the United States, residing at White Plains, in the county of Westchester and State of New York, have invented a new, original, and ornamental Design for a Combined Stand and Perfume Bottle Holder, of which the following is a specification, reference being had to the accompanying drawing, forming part thereof.

In the drawing

Fig. 1 is a front elevational view of a combined stand and perfume bottle holder showing my new design:

Fig. 2 is a side elevational view thereof.

I claim:

The ornamental design for a combined stand and perfume bottle holder, as shown.

FREDERICK M. BREEN.
